UNITED STATES PATENT OFFICE.

GEORGE A. WILKINS, OF AMSTERDAM, NEW YORK.

TAKE-UP FABRIC-ROLLER.

1,256,756.

Specification of Letters Patent. Patented Feb. 19, 1918.

Application filed November 15, 1916. Serial No. 131,449.

To all whom it may concern:

Be it known that I, GEORGE A. WILKINS, a citizen of the United States, residing at Amsterdam, in the county of Montgomery, State 5 of New York, have invented certain new and useful Improvements in Take-Up Fabric-Rollers; and I do hereby declare the following to be a full, clear and exact description of the invention, such as will enable others 10 skilled in the art to which it appertains to make and use the same.

This invention relates to knitting machines and has special reference to the take-up for such machines.

15 In the type of fabric receiving roller, or as it is known, the fabric roller, used in machines of this character each end of the roller is provided with a metallic pintle or journal so that the roller may be slidably and 20 rotatably mounted in the legs of the take-up frame. When this roller has received its load of knitted fabric it is customary to remove the roller with the fabric and dislodge the roller from the fabric by dropping one 25 of the journal ends on the floor of the mill. This results in frequent injury to the journal ends through bending or breaking and also results in damage to the floor by reason of these small journal ends digging into the 30 floor and destroying it.

One important object of the present invention is to provide a fabric roller of improved construction wherein provision will be made at one end of the roller for cushioning the shock against the floor so that the journal is not injured nor the floor destroyed.

In order to accomplish the object of providing a cushioning end it is found essential 40 that the size of the journal be increased and with the usual type of take-up, common at present on knitting machines it is found that this increased size of journal can not be used without special provision on account 45 of the narrowness of the slots in the take-up frame legs.

A second important object of the invention is to provide an improved guide attachment for this large journal which may be 50 readily applied to one of the legs of a take-up frame without requiring a reconstruction or a replacement of the entire frame.

With the above and other objects in view, as will be hereinafter apparent the invention 55 consists in general of certain novel details of construction and combinations of

parts hereinafter fully described, illustrated in the accompanying drawings, and specifically claimed.

In the accompanying drawings, like characters of reference indicate like parts in the several views, and:—

Figure 1 is a perspective view of a knitting machine take-up showing the improved device applied thereto. 65

Fig. 2 is a side elevation of the improved roller.

Fig. 3 is a side elevation of one of the legs of the take-up frame showing the attachment for the roller journal applied thereto. 70

Fig. 4 is a section on the line 4—4 of Fig. 3, disclosing the relationship of the roller journal with its guide and the legs.

Fig. 5 is a section on the line 5—5 of Fig. 2, showing the manner of inserting and 75 holding the elastic plug, used herewith, in position in the journal end.

Fig. 6 is a perspective view of the attachment for the leg.

In the embodiment of the invention here- 80 in illustrated there has been shown a take-up of the usual type indicated in general at A. This take-up is provided with the usual legs 10 forming part of its frame and the driving mechanism indicated in general 85 at 11. All of these parts are old and well known so that no further description is deemed necessary.

The present invention consists of a pair 90 of angle bars 12 which are connected together adjacent each end by a C-shaped clamp member 13 so that the two bars 12 may be held in proper spaced relation on one of the legs 10. In order to keep these two bars in their proper adjusted position 95 longitudinally of the leg the clamps 13 are provided with set screws 14 which bear against the legs when screwed up so as to lock the clamp in position.

The fabric roll used in connection here- 100 with consists of a body portion 15 which tapers from end to end and at the larger end of this body portion there is provided the pintle or journal 16. The other end of this body is reduced as at 17 and bored into 105 this reduced end and into the body is a recess 18 wherein is fitted a plug 19 of elastic material such as leather or solid rubber or the like, the extremity of the plug projecting somewhat beyond the end of the reduced 110 portion 17 as shown.

It is usual to make these rolls of wood and

in order to both prevent the splitting of the roll at this end and also to provide means to prevent its expansion about the plug to permit the latter to slip out there is provided a metallic ferrule or band 20 which fits tightly on the reduced end 17 and has its exterior turned to form a journal for this end of the roll. It will be noted that this reduced end is formed at the smaller end of the tapered roll. Owing to this construction the collar or ferrule 20 fits between the flanges of the angle bars and is rotatable therebetween and also slidably vertically along these bars in order to permit of the increase in size of the roll of fabric as the device operates. In addition, the spacing between the two angle bars permits the plug 19 to project between the angle bars so that this plug may be made sufficiently long to take up the shock of dropping without interfering with the operation of the roller either in rotating or in moving longitudinally of the angle bars.

When this device is used and the roll of fabric with its roller removed from the take-up then the roll and roller may be dropped together on the floor, the plug end being downward, with the result that the elastic plug 19 will serve as a bumper and will strike the floor without injuring it and owing to the tapering formation of the roller the latter will be readily dislodged from the roll of fabric which will drop on its end on the floor. Furthermore, the shock to the roller being absorbed by the plug 19 no danger exists of bending or breaking the

journal proper consisting of the reduced end 17 and collar or ferrule 20 since these parts never strike the floor.

There has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but it is wished to include all such as properly come within the scope claimed.

Having thus described the invention, what is claimed as new, is:—

1. A fabric receiving roller for knitting machine take-ups consisting of a body, a reduced end on said body, said end and body having a recess extending inward from the face of said end, an elastic plug fitting in said recess and projecting therefrom, and a ferrule fitted on the end and constituting a journal.

2. A fabric-receiving roller for knitting machine take-ups, having a ferrule at one end constituting a journal for that end of the roller and an elastic bumper carried by said end of the roller and projecting axially of the roller beyond the ferrule.

In testimony whereof I affix my signature in the presence of two witnesses.

GEORGE A. WILKINS.
